UNITED STATES PATENT OFFICE.

OSCAR J. THOMAS, OF PENINSULA, OHIO, ASSIGNOR OF ONE-HALF TO JOHN SEEBECK, OF SAME PLACE.

AUTOMATIC SEVERING DEVICE FOR PULP-MACHINES.

SPECIFICATION forming part of Letters Patent No. 417,689, dated December 17, 1889.

Application filed May 28, 1889. Serial No. 312,374. (No model.)

To all whom it may concern:

Be it known that I, OSCAR J. THOMAS, of Peninsula, in the county of Summit and State of Ohio, have invented certain new and useful Improvements in Automatic Severing Devices for Pulp-Machines; and I do hereby declare the following to be a full, clear, and exact description of the invention, such as will enable others skilled in the art to which it

10 pertains to make and use the same.

My invention relates to improvements in automatic severing devices for pulp-machines for severing and cleaving the pulp from the receiving-roller; and it consists in 15 certain features of construction and in combination of parts hereinafter described, and pointed out in the claims.

In the accompanying drawings, Figure 1 is a side elevation, and Fig. 2 is an end elevation, of a machine embodying my invention. Fig. 3 is a detail of bail g' . Fig. 4 is a detail of block E' and attachments.

A represents the bed of the machine, having attached upright housings A' for supporting the rollers B B' , the former being journaled in stationary boxes b , and the latter being journaled in boxes b' , adapted to slide up and down the housings with the up-and-down movement of roller B' . The lower 20 roller B is provided in the usual manner with an endless apron C , by means of which apron the pulp is brought to the rollers, the pulp being taken off the apron by the upper roller B' . When the pulp has accumulated to a desired thickness on this upper roller, the pulp is 25 severed lengthwise of the roller and taken off in a thick sheet, and such sheets, when afterward folded and dried, constitute the article of commerce from which large varieties of 30 paper are manufactured. Heretofore such severing of the pulp and stripping the same from the roller has usually been by hand, and the thickness of the sheet of pulp was, in the main, a matter of guess-work on the 35 part of the operator.

For automatically severing the pulp and cleaving the same from the roller when such pulp has reached a predetermined thickness, I provide the following mechanism, to wit: A 40 cross-bar D extends above and rests on one

of the sliding boxes b' of roller B' aforesaid, this cross-bar being connected by rods d with cross-bar D' , the latter in turn being connected by link d' with lever F near the fulcrum f of the latter. This peculiar construction of connecting mechanism is not essential, as any device whereby the said box b' is operatively connected with lever F near the fulcrum of the latter will answer the purpose.

E is the knife for severing the pulp, the 55 trunnions of this knife being journaled in brackets or hangers a' , connected with the housing. On the one trunnion of the knife is secured block E' , the same being fastened to the trunnions, preferably by means of set-screws e' . This block has at the top a longitudinal recess e , in which operates lever G , the latter being pivoted to the block at g , and the free end of the lever extending over the trunnions of the roller B and in position 60 to engage a cam B^2 , that is mounted on such trunnion of the upper roller. With each revolution of the upper roller cam B^2 tilts lever G upward, the lever returning to its horizontal or normal position by gravity after 65 the passage of the cam. Just below the bottom of recess e block E' is provided with a longitudinal bore, in which operates spindle H , this spindle extending through the block and having attached at the one end thereof 70 sheave H' and at the other end a hook-dog H^2 , the latter being adapted to engage bail g' . This bail is hinged to and depends from lever G , in position to swing toward and from the dog.

I is the disk, usually cast integral with block E' , this disk having a series of holes I' on the face thereof, the holes being equidistant from the axis of spindle H .

i and i' are pins adapted to fit in the different holes I' , and are interchangeable with the different holes. Sheave H' has a radially-projecting pin or lug h , adapted to engage pins i i' , the latter by such engagement serving as stops to limit the rotative movement of 90 the spindle and sheave in either direction, giving more or less movement to the sheave, according to the position of the pins in holes I' .

A cord J is fastened to the free end of le- 100

ver F, and from thence passes under idle sheaves j, j' , and from thence leads over sheave H', the free end of the cord having attached a poise J' for giving tension to the cord and 5 causing the latter to engage sheave H' with sufficient force to rotate the spindle and sheave by the movement of the cord.

In operating the device, suppose pin i to be placed in one of holes I', for instance, as 10 shown, and the sheave H' to have been adjusted until pin h bears against pin i , in which position of parts dog H² is supposed to be swung back some distance from bail g', knife E meanwhile depending in the inclined 15 position shown, with the edge of the knife separated a short distance from the face of roller B', so as to clear the pulp on the roller. As the pulp accumulates on roller B' the latter gradually rises, and by means of the connecting mechanism already described such 20 upward movement of the roller tilts upward lever F. This in turn draws on cord J, whereby sheave H' is rotated in the direction to move dog H² toward its engagement with 25 bail g', lever G meantime operating idly from its engagement with cam B². When the pulp on the roller has reached a predetermined thickness, the dog engages the bail, thereby locking lever G, so that with the next upward 30 movement of the lever block E' and knife E are actuated in the direction to cause the edge of the knife to engage or come in such close proximity to the face of roller B' as to sever the pulp on the roller and cleave it off, 35 the sheet of pulp thus disengaged falling onto table K. As the pulp is removed from roller B' the latter descends by gravity and rests again upon the apron, thus causing lever F to return to its normal or depressed 40 position, simultaneously with which poise J', by keeping the cord taut, reverses spindle II and disengages dog H' from the bail g', whereupon knife E and block E' are returned 45 by gravity to their normal position, with the knife-edge separated from the roller. By ad-

justing pin i in the different holes I', to cause dog H² to move a greater or shorter distance from the bail, the thickness of pulp that is allowed to accumulate on the roller B' is regulated, it being evident that with the dog farther removed from the bail more pulp must accumulate on the roller in elevating the latter the distance necessary to swing the dog forward to engage the bail. Pin i' is adjusted to stop the sheave in the other direction, so that the dog cannot swing under lever G and prevent the latter from reversing. When the dog is drawn up against the bail, the latter swings back out of the way without interfering with the tilting of lever G until such times as the dog shall have advanced so far that the bail, with the downward stroke of the lever, can swing by gravity under the shoulder of the dog for locking the dog and block E' together. 60

With the construction hereinbefore described, the parts having been adjusted to give the desired thickness to the sheet of pulp, the machine afterward operates automatically and requires no further attention, 70 and the sheets of pulp discharged from the machine are of a uniform thickness. 65

What I claim is—

In a pulp-machine, the combination, with 75 a feed-roller journaled in movable boxes, and a knife mounted on a shaft and adapted to be forced by the movement of the feed-roller into contact with the pulp on said feed-roller, of mechanism connecting the knife and roller, whereby the former is automatically 80 brought into contact with the latter when the latter has been elevated a predetermined distance, substantially as set forth.

In testimony whereof I sign this specification, in the presence of two witnesses, this 13th day of March, 1889.

OSCAR J. THOMAS.
